United States Patent Office.

WILLIAM KEARNEY, OF BELLEVILLE, NEW JERSEY.

Letters Patent No. 105,948, dated August 2, 1870.

IMPROVEMENT IN GRATE-BARS.

The Schedule referred to in these Letters Patent and making part of the same

To all whom it may concern:

Be it known that I, WILLIAM KEARNEY, of Belleville, in the county of Essex and State of New Jersey, have invented a new and useful Improvement in Grates for Furnaces; and I do hereby declare that the following is a full, clear, and exact description thereof, which will enable others skilled in the art to make and use the same, reference being had to the accompanying drawing forming part of this specification.

Figure 1 represents a vertical transverse section of my improved grate.

Figure 2 is a vertical longitudinal section of the same.

Similar letters of reference indicate corresponding parts.

My invention relates to improvements in that class of grate-bars for furnaces which is provided with longitudinal, transversely-slotted brace-bars. Hitherto these brace-bars have been so constructed as to warp or bend laterally, thus failing to perform their intended office.

It is the object of my invention to obviate this difficulty, and

It consists in applying a transverse bridge or support between the brace and grate-bars, as herein shown and described.

A in the drawing represents a grate, composed of a suitable number of grate-bars, *a*, which are held the proper distance apart by blocks *b*, or otherwise.

B is the brace. The same has both ends bifurcated and secured to the middle grate-bars near to the ends of the same, thereby binding the grate lengthwise, and causing it to retain its shape.

To the middle of the brace *B* is secured a transverse bridge, *C*, which has upward projecting arms, *c c*, that reach to the several grate-bars, as shown in fig. 1.

These arms being secured to the grate-bars, hold them the requisite distance apart.

Having thus described my invention,

I claim as new and desire to secure by Letters Patent—

The transverse bridge *C*, secured to and combined with the brace *B*, and provided with fingers *c*, substantially as and for the purposes herein shown and described.

WILLIAM KEARNEY.
